J. & T. A. BOYD.

Pirn or Cop Winding Machinery.

No. 236,300.

Patented Jan. 4, 1881.

UNITED STATES PATENT OFFICE.

JOHN BOYD AND THOMAS A. BOYD, OF SHETTLESTON, COUNTY OF LANARK, SCOTLAND.

PIRN OR COP WINDING MACHINERY.

SPECIFICATION forming part of Letters Patent No. 236,300, dated January 4, 1881.
Application filed April 5, 1880. (No model.) Patented in Great Britain June 27, 1873, and December 1, 1874.

To all whom it may concern:

Be it known that we, JOHN BOYD and THOMAS ALEXANDER BOYD, subjects of the Queen of Great Britain, and residing at Shettleston, in the county of Lanark, Scotland, have invented certain Improvements in Pирн or Cop Winding Machinery, (for which we obtained British Letters Patent dated June 27, 1873, No. 2,226, and December 1, 1874, No. 4,119,) of which the following is a specification.

Our invention relates to the winding of yarns on pирнs or in cops, to be used in shuttles or otherwise, and to machinery of the kind in which, on the winding of a pирн or cop being completed, an automatic separation of the pирн or of the cop-spindle takes place, so that it becomes disconnected from its driving part and its motion is stopped. The machine is made for winding horizontally-placed pирнs or cops at its two opposite sides, and the winding-spindles of one side alternate with those of the other side, and their inner or back ends project across, in some positions, nearly to the other side of the machine. To prevent the said inner or back ends of the opposite and alternate spindles from interfering with the pирнs or cops at either side, certain curved plates or shields are provided to cover the spindle ends and their brackets, and to form troughs under the pирнs or winding ends of the spindles, to catch the full cops as they are pushed off the end of the spindle. The series of alternate winding-spindles which extend horizontally across the machine are carried by two parallel rails near the middle of the machine, and are driven by a longitudinal shaft placed just above them, and carrying a driving bevel-wheel for each two spindles, every second spindle receiving motion through spur-pinions, the main object of passing the alternate spindle through the same two rails and constructing the parts in the manner described being to reduce the width of the machine.

Figure 1 is a transverse vertical section of a pирн or cop winding frame, and shows the several parts combined together. Figs. 2, 3, and 4 are enlarged detached views of the fixed bracket for the weighted lever; Figs. 5 and 6, views of the compensating-lever for the

yarn; Fig. 7, Sheet 2, an enlarged plan view, partly in section, of three of the winding-spindles and their parts; Fig. 8, a section on the line A A, Fig. 7; Fig. 9, a detached side view of the shield for the spindles; Fig. 10, a detached side view of the swivel-piece to be adapted to the end of the spindle; Figs. 11 and 12, a plan and side view, respectively, of the weighted lever; Figs. 13 and 14, a plan and side view, respectively, of the movable bracket; Fig. 15, a section of a spindle adapted to its slotted tube; and Figs. 16, 17, 18, and 19, detached views of the clutch devices for connecting the cop-spindle to the winding-spindle.

The main framing of the machine consists of transverse vertical frames 20, connected by two inner longitudinal rails, 21, near the middle and an outer longitudinal rail, 22, along each side. The winding-spindles 23 are placed horizontally and transversely, and pass through the inner rails, 21, those appertaining to one side of the machine alternating with those appertaining to the other side.

In Fig. 7 two winding-spindles, 23, appertaining to one side, are shown along with a part of an intermediate spindle appertaining to the other side. The winding-spindles 23 pass through bearing-bushes screwed into the inner rails, 21, and through driving-tubes 24, which are held between the rails, and are formed with spur-pinions 25, while each alternate one is also formed with a bevel-pinion, 26.

The driving motion is communicated by a central longitudinal shaft, 27, which has on it a number of bevel-wheels, 28, there being one for each pair of spindles. Each bevel-wheel 28 gears with the bevel-pinion 26 on one of a pair of spindle-tubes, 24, and the motion is communicated to the other of the pair by the spur-pinions 25. The tubes 24 drive the spindles 23 by means of slots, into which keys or feathers on the spindles project, as shown in cross-section in Fig. 15, this arrangement allowing the spindles 23 to move endwise through their tubes 24 while being made to rotate by the tubes.

On the inner or back end of each winding-spindle 23 there is hung a swivel-piece, 29, (shown detached in side elevation in Fig. 10.)

The spindle is made with a shoulder and a reduced end, and when the parts are put together a nut, 30, is screwed up to the shoulder, this nut occupying a recess formed for it in 5 the swivel-piece 29. The swivel-piece 29 is bored so that its outer part fits loosely on the reduced end of the spindle and its inner part on the unreduced part, and pressure between the spindle and swivel-piece acts on the end 10 of the spindle when in one direction and on the inner face of the nut 30 when in the other direction.

The swivel-piece 29 is formed with lateral indentations, in which fit freely prongs 31 of the 15 forked end of a slide or movable bracket, 32, (shown in plan in Fig. 13 and in side elevation in Fig. 14.) This movable bracket 32 has jointed to it a weighted lever, 33, (shown in plan in Fig. 11 and in side elevation in Fig. 12,) 20 and the two work in connection with a stationary bracket, 34, which is shown in plan in Fig. 2, in side elevation in Fig. 3, and in end elevation in Fig. 4, and which is bolted up to the under sides of the inner rails, 21. The movable bracket 32 is supported and guided on 25 guides 35 36, formed for it on the ends of the fixed bracket 34, these surfaces, which are shown in section in Fig. 1, allowing just enough room between them and the under sides of the rails 21 for the easy movement of the movable bracket 32. After the movable bracket 32 is placed in position, a retaining-piece, 37, is 30 screwed to the fixed bracket 34 at one (36) of the guide-surfaces, to prevent its displacement. 35 The back end of the movable bracket 32 is formed with a turned-up forked part, 31, which embraces the swivel-piece 29 on the inner end of the winding-spindle 23, as hereinbefore indicated, and the other end is formed with a 40 horn, 38, which passes up at the side of the shield 39, and serves as a handle for moving the movable bracket 32 by, and by the connection at the inner end moving the winding-spindle 23 also.

45 The weighted lever 33 is, by one or other of a series of holes which admit of the connection being changed to suit different lengths of pirn or cop, jointed to a downward projection, 40, on the movable bracket 32, near its 50 inner end, and a part of the weight-lever works between a slotted or double part of the fixed bracket 34, projections 41, formed on the opposite sides of the lever, resting on the upper edges of the double part of the bracket. These 55 upper edges of the double part of the fixed bracket 34 are inclined in opposite directions from a high point, 42, which is near one end, and while the winding of a pirn or cop is proceeding the weighted lever 33 rests on the 60 longer incline. As the gradual accumulation of yarn on the pirn or spindle forces back the winding-spindle 23, and with it the sliding bracket 32, the weighted lever 33 is drawn up the long incline, its weight and resistance 65 to that movement serving to press the pirn or cop to the desired extent into the conical cup

43, which is employed, as usual, to impart compactness or density to the yarn as it is being wound. As soon as the projections 41 of the weighted lever 33 reach the highest point, 70 42, of the inclines, they proceed to pass down the short incline, and then the tendency of the weighted lever is not to resist the backward movement of the winding-spindle 23, but to make it move back, and this causes the 75 winding-spindle to become separated from the pirn or cop spindle, the further inward movement of which is prevented by a stop, as hereinafter explained. It will thus be understood that the length of pirn or cop wound is 80 determined by the extent of the inward movement of the winding-spindle 23, which takes place from the commencement of the winding action until the highest point, 42, of the inclines is reached by the weighted lever 33. 85

The conical cups 43 are fixed to the outer longitudinal rails, 22, and the traverse guide-fingers 44 are fixed to rocking shafts 45, carried inside the outer rails, 22, and worked by means of levers fixed on them and connected 90 to an eccentric on the longitudinal shaft 27.

The yarn to be wound is shown as proceeding from a reel, 46, on one side of Fig. 1, and from a bobbin, 47, as shown on the other side, up to a compensating-lever, 48, which is shown 95 separately in plan and side elevation in Fig. 5. The movement of the compensating-lever 48 is limited by horns or projections near its pivot, these encountering a boss on the small bracket in which the pivot or center-pin of the 100 lever is fixed. A wire-spring, 49, is coiled round the center-pin and bears on a projection on the lever 48, this spring causing the lever end, which has a guide-button, 50, on it for the yarn to pass round, to rise when the yarn is being wound 105 on the smaller end of the cop or pirn surface, and allowing it to yield downward when the 110 yarn is being wound on the larger part, and thus tending to equalize the rate at which the 115 yarn is drawn from the reel 46 or bobbin 47. 120 With some yarns of a slippery and elastic nature the compensating-lever 48 has not sufficient control when fitted with a single guide-button 50, and in such cases we provide it with two buttons 50, as shown in plan and side elevation in Fig. 6. The yarn can be led round the two guide-buttons in various ways, accordingly as more or less tension or control is in practice found necessary. In Fig. 1 the compensating-lever 48 at the right-hand side is 125 shown as fitted with two buttons 50.

Each winding-spindle 23 has fixed on what may be termed its "frontend" a clutch-disk, 51, (shown separately in Figs. 16 and 17,) having on its front face two tapered clutch projections 125 or teeth, 52, adapted for easily engaging in counterpart recesses in a disk, 53, (shown separately in Figs. 18 and 19,) which has fixed in it a spindle, 54, for winding cops on, which spindle is afterward withdrawn from the cop. 130

When winding on pirns, the pirn-bottoms are formed with recesses to engage with the clutch-

teeth 52; or pirn-holders consisting of spindled disks like that shown in Figs. 18 and 19 may be provided.

The troughs or shields 39, as shown in Figs. 5 7, 8, and 9, consist each of a thin metal plate, 39, fixed at its outer and inner ends, respectively, to an outer and inner rail, 22 21. This plate 39 is curved so as to pass over the inner end of one winding-spindle 23 and under the 10 front end of the adjacent winding-spindle, and the part passing under the front end of a winding-spindle has a slot formed in it, (indicated by dotted lines in Figs. 7 and 9,) in which there is fixed a stop, 55, to arrest the disk 53 when 15 the winding-spindle 23 is drawn back at the completion of a pirn or cop, as hereinbefore explained, this stop 55 being adjustable to suit different lengths of pirn or cop. When the 20 pirn or cop is thus pushed off the winding-spindle it is caught by the trough, instead of being allowed to fall down through the frame, where it might cause a stoppage of the machine or a breakage of some part. These troughs 25 also serve, with their overhanging portions, to prevent interference between the front ends of the winding-spindles 23 and the cops on them and the inner ends of the adjacent spindles from the other side of the machine. There is also a slot in the other part of the shield, to give access for oiling the swivel-piece 29.

We claim as our invention in pirn or cop winding machinery—

1. The frame having two inner rails, 21, the slotted tubes 24, geared together in pairs, each 35 alternate tube having a bevel-wheel, and a longitudinal shaft having bevel-wheels geared therewith, in combination with winding-spindles 23, passing through the same two rails al-

ternately to opposite sides of the machine, and having keys or feathers adapted to said slotted tubes, all substantially as set forth. 40

2. The combination of the main frame and driving mechanism with fixed bracket 34, weighted lever 33, movable bracket 32, and winding-spindle adapted to move with but turn 45 independently of the said bracket, all substantially as set forth.

3. The combination of the main frame, winding-spindle, and driving mechanism with the movable bracket 32, adapted to guides on the 50 frame, the swivel-piece 29, weighted lever 33, and fixed bracket 34.

4. The combination of the frame, winding mechanism, and winding-spindles adapted to slide longitudinally in the frame, with stops 55 55 and troughs 39 below the ends of said spindles, to catch the pirns or cops as they are pushed off the ends of the spindles, substantially as set forth.

5. The combination of the frame, winding mechanism, and adjacent alternating winding-spindles 23 with stops 55 and S-shaped troughs or shields 39, carrying said stops, and adapted to serve the double purpose of catching the cops or pirns when they are pushed off the ends 65 of the spindles, and of preventing interference between adjacent spindles, all substantially as described. 60

In testimony whereof we have signed our names to this specification in the presence of 70 two subscribing witnesses.
